To all whom it may concern:

Be it known that I, Adolph M. Kemper, a citizen of the United States of America, residing in Larchmont, county of Westchester, and State of New York, have invented a new, original, and ornamental Design for a Textile Fabric, of which the following is a specification, reference being had to the accompanying drawing, forming part thereof, wherein.

Figure 1 is a plan view of a textile fabric showing my new design.

A cross sectional view taken on a vertical stripe in Figure 1, corresponding to the horizontal, light stripe 2—2 in the same figure, will be similar to Figure 2.

I claim:

The ornamental design for a textile fabric, substantially as shown and described.
